UNITED STATES PATENT OFFICE.

FRANK MORGENTHALER, OF RIESEL, TEXAS.

FENCE-POST EXTRACTOR.

SPECIFICATION forming part of Letters Patent No. 656,747, dated August 28, 1900.

Application filed April 27, 1900. Serial No. 14,601. (No model.)

To all whom it may concern:

Be it known that I, FRANK MORGENTHALER, a citizen of the United States, residing at Riesel, in the county of McLellan and State of Texas, have invented a new and useful Fence-Post Extractor, of which the following is a specification.

My invention relates to a novel fence-post extractor; and one object in view is to provide an apparatus of this character so constructed and arranged that it may be located alongside of a fence-post and operated to exert great leverage to pull the post in a direct vertical line.

15 A further object of the invention is to constitute the operative parts of the apparatus as guides which serve to retain the post in an upright position while being extracted.

Ordinarily in devices of this general character the frame of the extractor is so constructed as to necessitate the location of the extracting mechanism directly over the post. By the employment of my extractor there is no necessity for any of the operative parts being extended over the post, inasmuch as the drums are located in vertical alinement and are presented directly against the side of the post, the frame being stayed by supports or braces which extend only from that side of the 30 drum-supporting uprights opposite the post.

To the accomplishment of the objects stated my invention consists in the novel construction and arrangement of the parts of the extractor, all as will be hereinafter fully described, illustrated in the accompanying drawings, and succinctly defined in the appended claims.

In said drawings, Figure 1 is a perspective view of my extractor, illustrating this application. Fig. 2 is a side elevation thereof; and Fig. 3 is a central longitudinal section, the elevated or extracted position of the post being shown in dotted lines.

Referring to the numerals of reference used 45 to indicate like and corresponding parts in the several views, 1 and 2 designate parallel uprights braced by suitable cross-bars 3 and 4, located approximately adjacent to their upper and lower ends and preferably at their 50 front and rear edges, respectively, and 5 and 6 indicate a pair of supports or braces connected at their upper ends to the standards

1 and 2 and downwardly divergently related thereto in order to constitute a brace to prevent rearward inclination of the standards— 55 that is to say, in the direction of the post— when the extractor is in use. The supports or braces 5 and 6 are preferably connected adjacent to their lower ends to the standards, as by side bars 7. 60

8 indicates an operating and guide drum having terminal trunnions 9, journaled in the standards and designed to be rotated by a crank 10, keyed or otherwise secured upon one of the trunnions beyond the adjacent 65 standard. Around this guide and operating drum, the periphery of which extends slightly beyond the edges of the standards, is wound an operating-cable 11, which passes upwardly from the rear side of the drum and is fastened to and designed to be wound upon an enlarged sheave 12, provided with a peripheral groove 13 for the reception of the cable and keyed or otherwise secured upon the extracting-drum 14, journaled, like the drum 8, 70 between the uprights, but preferably of somewhat less diameter, in order that when the extracting-cable 15 is wound thereon in the operation of the machine the extreme diameter of the drum and wound cable will approximate the diameter of the drum 8. The extracting-cable 15 is terminally fixed, as indicated, to the drum 14 and depends from the rear side of said drum and may be attached in any suitable manner to a fence-post 75 16. If desired, a guide-block 17 may be mounted upon the upright 2 in proximity to the drum 8 to prevent the operating-cable from working between the bearing-faces. 80

The operation of my device is as follows: 90 Supposing the extraction of the fence-post shown in Fig. 1 to be desired, my extractor is presented alongside of the post, so that its upper end will be in contact with the drum 8. The cable 15 is now attached to the post in 95 any desired manner, and the crank 10 is turned in the direction indicated by the arrow. The effect of this will be to cause the drum 8 to be rotated in the direction of the arrow to wind the operating-cable thereon 100 and to cause the unwinding of said cable from the sheave 12. This operation will obviously effect the rotation of the sheave and the extracting or cable drum 14 at a less rate of

speed than the speed of the drum 8, but with a corresponding increase of force being exerted upon the extracting-cable 15, which increase is of course due to the leverage gained 5 from the differential diameters of the operating-drum and sheave, the radius of the former corresponding to the short arm of a lever, of which the radius of the latter constitutes the long arm. As the post is gradually 10 drawn upwardly by the operating-cable it is guided in its movement and is retained in its true vertical position by contact with the operating-drum 8, which guides the post in its upward movement. As the post is drawn 15 still higher its upper end contacts with the cable 15, wound upon the drum 14, and is now held firmly against both drums and is guided by them. It will therefore be observed that my extractor is of such peculiar 20 construction and arrangement that its front portion is straight or flat to facilitate the movements of the operator and that it is supported or braced only from the side opposed to the post, so that the latter as it is drawn 25 up travels along the face of the frame and is guided by both of the drums. The braces serve to prevent sidewise tilting of the frame, as well as to prevent it from being tilted in the direction of the post.

30 While the present embodiment of my invention is believed at this time to be preferable, I do not desire to limit myself to the structural details defined; but, on the contrary, I reserve the right to effect such 35 changes, modifications, and variations as may come properly within the scope of my invention.

What I claim is—

1. In a fence-post extractor, the combination 40 with a frame comprising parallel uprights, and supports extending from one side only of said uprights, of a pair of horizontal drums carried by the uprights in vertical alinement, means for operating said drums,

and a cable carried by one of said drums and 45 designed to be attached to a fence-post.

2. In a fence-post extractor, the combination with a frame comprising a pair of parallel uprights, and supports extending from one side only of said uprights, of an operating- 50 drum and an extracting-drum journaled in the uprights and located in vertical alinement, a sheave carried by the extracting-drum, an operating-cable passed around the operating-drum and extending from the periphery of said drum at the rear of said frame to the periphery of the sheave at the front of the frame, an extracting-cable passed around the extracting-drum and extending from the periphery thereof at the rear of the frame, 55 and a crank operatively connected to the operating-drum, whereby the rotation of the latter effects the opposite rotation of the extracting-drum to pull the post in a direct vertical line and in contact with both drums 60 which serve as guides for maintaining the vertical position of said post.

3. In a fence-post extractor, the combination with a frame comprising a pair of uprights supported from one side only, of a pair 70 of horizontal drums journaled in the uprights and located in vertical alinement, means for operating said drums, gearing intermediate of said drums, and an extracting-cable wound upon the upper drum, said upper drum being of slightly-less diameter than the lower drum in order to make the combined diameter of the upper drum and the rope wound thereon substantially equal to the diameter 75 of the lower drum.

In testimony that I claim the foregoing as my own I have hereto affixed my signature in the presence of two witnesses.

FRANK MORGENTHALER.
